UNITED STATES PATENT OFFICE.

ALFRED WILLCOX, OF LONDON, ENGLAND.

PORTABLE MORTAR, CONCRETE, OR LIKE MIXING MACHINE.

SPECIFICATION forming part of Letters Patent No. 686,567, dated November 12, 1901.

Application filed July 8, 1901. Serial No. 67,538. (No model.)

To all whom it may concern:

Be it known that I, ALFRED WILLCOX, a subject of the King of Great Britain, residing at 25 Norroy road, Putney, London, England, 5 have invented certain new and useful Improvements in and Connected with Portable Mortar, Concrete, or Like Mixing Machines, of which the following is a specification.

The object of this invention is improvements connected with portable mortar, concrete, or like mixing machines whereby such machinery is rendered more efficient in action and the material more effectually mixed, the vehicle being so constructed that the sand, 10 lime, cement, &c., are readily placed in the mixing-chamber and the water properly supplied for a thorough saturation, the material when thoroughly mixed being easily released for filling carts, barrows, trolleys, or the like 15 for removal to the place required.

My invention will be understood from the following description, aided by the accompanying drawings, in which—

Figure 1 is a side sectional elevation of a 20 complete machine. Fig. 2 is a side elevation of a complete machine. Fig. 3 is a plan of the machine with the water-trough removed.

For the purpose of my invention I construct a framework A on wheels B, so that the whole 25 apparatus can be moved from place to place, and at the front and rear I provide platforms C D, the center being occupied by a tank E, having the bottom shaped to form, so to speak, the segments of two circles F G. In this 30 mixing-tank E, I fit two axles H I at a distance from each other, these being provided with arms J, carrying blades K, so arranged that their edges have a travel in close proximity to the circular part of the walls of the tank 35 E, and such arms J are so arranged on each 40 axle H I that during the revolving of such axles H I the arms J follow one another in succession, the axles H I being geared together outside the tank by wheel L M, another 45 gear-wheel N on the opposite side of the tank being in gear with a toothed wheel P on the pulley-wheel Q or crank-handle axle or other 50 connection for the prime mover.

Above the center of the tank E is situated 55 a water-reservoir R, this carrying a perforated tube B, extending across the center of the

tank E, the supply of water being controlled by a valve T.

The center of the bottom of the tank E is formed by the apex of the two circular walls 55 F G, and at this point I form a hinge-joint U, carrying doors V, forming part of the circular walls F G, and such doors V are connected together by links W, controlled by a rod X from a hand-lever Y, so that on the operation 60 of the hand-lever Y in one direction the doors or flaps V can be opened to discharge the contents into a truck Z, (shown in dotted lines,) van, or other receptacle, and by a reverse motion of the handle Y the doors or 65 flaps can be closed, these then forming part of the walls F G of the circular portion and up which the beaters or mixer-blades K travel.

The portable apparatus can be secured in any desired position, and the mixer can be 70 operated by hand or through a belt and pulley or other gear from a stationary prime mover, or the prime mover may form part of the apparatus.

One platform C is provided with a guide or 75 track a for the barrow (not shown) containing the material to be placed in the tank or mixing-chamber, so that the barrow-load will be emptied in the same place in the tank E, the tank E being provided with a slope b to 80 assist this operation, so that on the filling of the tank with the required proportion of each material, whether it be sand and lime or cement or otherwise, a revolution of the arms J and blades K of one axle H will carry the 85 material toward the center to the arms J and blades K of the other axle I, when it will be met by the arms and blades of the second axle I to be carried onto the arms and blades of the first axle H for a further movement, the material 90 passing from one set of blades to the other until a thorough amalgamation takes place, the water for making the material wet to form the concrete or plaster being supplied at between the two axles H I from the perforated pipe S. On the thorough admixing of the material the operation on the lever Y will 95 open the doors or flaps V in the bottom for discharge purposes.

The blades K are made with angled edges 100 and with the front edge c of greater width than the back d and are bolted to a right-

angled piece *e* of the arms *J*, so as to be easily removed and new ones replaced when worn, and by reason of the edges of the blades *K* traveling close to the walls of the tank *E* all 5 blocking by stones or other material is avoided, and consequently the amount of power required to drive the axles is reduced.

What I claim, and desire to secure by Letters Patent, is—

- 10 In a portable mortar concrete and like mixing machine, the combination of frame *A* and wheels *B*, having platforms *C* *D*, tank *E* having circular walls *F* *G* and doors *V* axles

H *I*, carrying arms *J* and blades *K*, gear-wheels *L* *M* *N* water-reservoir *R*, perforated 15 pipe *S* extending across center of tank *E*, track *a* on platform *C*, and slope *b* in tank *E*, all arranged and acting substantially as set forth.

In testimony whereof I have hereunto set 20 my hand in presence of two subscribing witnesses.

ALFRED WILLCOX.
